(57) **CLAIM**

The ornamental design for a knee pad, as shown and described.

DESCRIPTION

FIG. 1 is a front perspective view of my design;

FIG. 2 is a bottom plan view;

FIG. 3 is a top plan view;

FIG. 4 is a front elevational view;

FIG. 5 is a rear elevational view;

FIG. 6 is a left side elevational view;

FIG. 7 is a right side elevational view;

FIG. 8 is a front perspective view of the exterior shell of my design;

FIG. 9 is a bottom plan view of the exterior shell;

FIG. 10 is a top plan view of the exterior shell;

FIG. 11 is a front elevational view of the exterior shell;

FIG. 12 is a rear elevational view of the exterior shell;

FIG. 13 is a left side elevational view of the exterior shell;

FIG. 14 is a right side elevational view of the exterior shell;

FIG. 15 is a front perspective view of the interior support of my design;

FIG. 16 is a bottom plan view of the interior support;

FIG. 17 is a top plan view of the interior support;

FIG. 18 is a front elevational view of the interior support;

FIG. 19 is a rear elevational view of the interior support;

FIG. 20 is a left side elevational view of the interior support; and,

FIG. 21 is a right side elevational view of the interior support.

FIGS. 1 through 7 depict the knee pad with the exterior shell and interior support components assembled whereas for ease of illustration FIGS. 8 through 14 depict only the exterior shell of the knee pad without its interior support and also for ease of illustration FIGS. 15 through 21 depict only the interior support of the knee pad without its exterior shell.
